UNITED STATES PATENT OFFICE

140,062

DESIGN FOR A COMBINED PICTURE FRAME AND COMPACT CASE

Raphael Randolph, La Grange, Tex.

Application November 2, 1944, Serial No. 116,110

Term of patent 7 years

(Cl. D86—10)

To all whom it may concern:

Be it known that I, Raphael Randolph, a citizen of the United States, residing at La Grange, in the county of Fayette and State of Texas, have invented a new, original, and ornamental Design for a Combined Picture Frame and Compact Case, of which the following is a specification, reference being had to the accompanying drawing, forming part thereof.

Fig. 1 is a perspective view of a combined picture frame and compact case showing my new design.

Fig. 2 is a cross-sectional view taken on the line 2—2 of Fig. 1, and

Fig. 3 is an end elevational view thereof showing the photograph insert slot.

I claim:

The ornamental design for a combined picture frame and compact case, substantially as shown.

RAPHAEL RANDOLPH.
